CLAIM

[21] Appl. No.: **29/090,209**

We claim the ornamental design for a front surface of a motorcycle cam gear cover, as shown and described.

[22] Filed: **Jul. 2, 1998**

DESCRIPTION

[51] LOC (6) Cl. **12-11**

FIG. 1 is a front elevational view of the front surface of a motorcycle cam gear cover showing our new design; and, FIG. 2 is an enlarged front elevational view thereof. The broken lines shown in both views are for illustrative purposes only and form no part of the claimed design.
